COT

Curt W. Kroha, Fort Walton, Fla.

Application September 8, 1950, Serial No. 183,815

5 Claims. (Cl. 5—115)

1

My invention is an improved form of folding cot having for its principal object the provision of a cot which may be quickly and easily folded up to form a small compact package, and which readily unfolds to form a comfortable sleeping surface.

Another important object of my invention is to provide a cot of the character mentioned wherein the sleeping surface comprises a tightly stretched canvas supported on springs in such a way that when the cot is opened a plurality of springs yieldably tension the canvas, but when the cot is closed, the tension is relaxed so that the canvas will not be permanently stretched by continuously being under tension.

Still another object of my invention is to provide a folding cot having a headboard which forms an extension of the sleeping surface when the cot is open, but which folds over the canvas when the cot is closed, the board protecting the canvas and simultaneously affording a closure to maintain the cot in folded position.

Another object is to provide a folding cot having means for maintaining the cot in open position against the tension of the canvas.

A further object is the provision of a folding cot which is strong and stable and which is economical to construct.

Other objects and advantages will become apparent during the discussion of the drawings, wherein:

Fig. 1 is a side elevation of the cot in open position;

Fig. 2 is a plan view of the cot in open position;

Fig. 3 is a side elevation of the cot in folded position;

Fig. 4 is an end elevation of the cot in folded position; and

Fig. 5 is a sectional view along line 5—5 of Fig. 1.

Referring to the drawings, the cot comprises a pair of parallel vertically disposed sets of toggle links 1 and 2 each set having crossed members 1a, 1b, 2a and 2b, respectively. These links are pivotally joined at their bottoms by pins 3 and 4 which are fixed in the respective ends of cross-bars 5. Similarly, the centers of the links are pivotally joined by pins 6 and 7 fixed in the ends of cross-bars 8. The upper ends of the links are pivotally joined by pins 9 and 10 having eyes 9a and 10a, respectively, at their inner ends and enlarged outer ends as at 9b and 10b, Fig. 5.

A canvas sleeping surface 11 is stretched tightly along the top of the cot and is secured at its

2

respective ends to cross-bars 12 and 13, Fig. 2, at the upper opposed ends of the toggle links 1 and 2. The canvas 11 may have parallel webbing strips 11a and 11b sewed to it parallel to its sides and spaced inwardly therefrom, the strips carrying pairs of grommets 11c and 11d, respectively. The canvas 11 is laterally tensioned by two sets of coil springs 14 and 15, Figs. 2 and 5, which stretch the canvas 11 tightly between the respective pairs of springs to form a yielding comfortable sleeping surface. The ends of the springs are secured in the grommets at one end and in the eyes at the other end. If desired, the strips 11a and 11b may be eliminated in which case the grommets 11c and 11d would be set in the sheet 11 itself along the sides thereof.

A headboard 16 is pivotally mounted near the cross-bar 12 by brackets 16a pivoted on the respective pins 9b and 10b. The brackets 16a are so formed as to allow the headboard 16 to open outwardly only as far as it is shown in Fig. 1, but to permit the board to fold over the tops of the toggle links, as shown in Fig. 3. A hook 17 and eye 11a serve to hold the board in closed position, the eye being mounted on the cross-bar 13.

Locking means is also provided for maintaining the cot in open position against the tension of the canvas tending to close the toggle links. The present embodiment shows arms 18 and 19 pivoted at their inner ends by a pin 20 and pivotally fixed as at 18a and 19a to adjacent parallel members of the toggle links 1a and 2a. A stop 20a is provided to prevent the arms 18 and 19 from pivoting downwardly beyond horizontal alignment.

In operation, the cot is initially folded as shown in Figs. 3 and 4. The hook 17 is released from the eye 11a and the headboard 16 is pivoted outwardly until it is nearly horizontal. Then the toggle links 1 and 2 are pulled out until the canvas 11 is tight, the links being locked open by arms 18 and 19 when in their horizontal position, Fig. 1. It should be noted that when the canvas 11 is limp, the inner ends of the adjacent pairs of springs 14, or springs 15, pull together along arcs the centers of which lie in the eyes 9a (or 10a). Therefore, in this position the lateral distance across the canvas 11 between the grommets 11a and the grommets 11d is decreased to relieve the tension on the opposed springs. Conversely, when the canvas is longitudinally tightened, the adjacent grommets 11c, or 11d, are pulled apart so that the angle between adjacent springs, which are connected at their outer ends

to the same eye, is increased so that the springs are all stretched tightly to laterally tension the canvas 11. By this means, the canvas is relaxed when the cot is folded so that it will not be permanently stretched by a continuous tension.

I do not limit my invention to the exact form shown in the drawings, for obviously changes may be made within the scope of the claims.

I claim:

1. A folding cot comprising a longitudinally extensible frame including parallel lazy-tong side members connected together; an eyelet fixed to each upper lazy-tong joint; a fabric sheet suspended at its ends on said frame to be stretched lengthwise as said frame is moved into extended position, and said sheet having along each side a series of pairs of longitudinally spaced grommeted holes, the mid-point of the spacing between the holes of each pair lying opposite an eyelet; and tensioning means comprising pairs of tension springs, the springs of each pair having their outer ends fixed in an eyelet and their inner ends respectively fixed in one hole of each associated pair of holes.

2. A folding cot comprising a longitudinally extensible frame including parallel lazy-tong side members connected together; an eyelet fixed to each upper lazy-tong joint; a fabric sheet suspended at its ends on said frame to be stretched lengthwise as said frame is moved into extended position, and said sheet having along each side a series of pairs of longitudinally spaced grommeted holes, the mid-point of the spacing between the holes of each pair lying opposite an eyelet; and tensioning means comprising pairs of tension springs, the springs of each pair having their outer ends fixed in an eyelet and their inner ends respectively fixed in one hole of each associated pair of holes, the spacing between the holes of a pair and the characteristics of the springs being so chosen as to cause tensioning of the springs when the cot is opened up for use and the inner ends of the springs are separated by said spacing, and to allow relaxation of said tension when the cot is folded.

3. A folding cot comprising a longitudinally extensible frame including parallel lazy-tong side members connected together; an eyelet fixed to each upper lazy-tong joint; a fabric sheet suspended at its ends on said frame to be stretched lengthwise as said frame is moved into extended position, and said sheet having along each side a series of pairs of longitudinally spaced grommeted holes; and tensioning means comprising pairs of tension springs, the springs of each pair having their outer ends fixed in an eyelet and their inner ends respectively fixed in one hole of each associated pair of holes, the midpoint of the spacing between each two grommeted holes

in the canvas when stretched lying opposite to an eyelet and such two holes being each separated from such eyelet by a distance greater than the relaxed length of the spring connecting the hole and eyelet.

4. A folding cot comprising a longitudinally extensible frame including parallel side members connected together; a row of eyelets longitudinally spaced when the frame is extended and fixed along each side member near the top thereof, the eyelets of each row facing inwardly of the frame; a fabric sheet suspended at its ends on said frame and adapted to be stretched lengthwise when said frame is moved into extended position; longitudinal fabric strips affixed to the said sheet at the respective sides thereof, said strips having longitudinal series of pairs of longitudinally spaced grommeted holes therein, the mid-points of the spacing between the holes of each pair lying opposite an eyelet; and tensioning means comprising pairs of tension springs, the springs of each pair having their outer ends fixed in an eyelet and their inner ends respectively fixed in one hole of each associated pair of holes.

5. A folding cot comprising a longitudinally extensible frame including parallel side members connected together; a row of eyelets longitudinally spaced when the frame is extended and fixed along each side member near the top thereof, the eyelets of each row facing inwardly of the frame; a fabric sheet suspended at its ends on said frame and adapted to be stretched lengthwise when said frame is moved into extended position, and said sheet having along each side a series of pairs of longitudinally spaced grommeted holes, the mid-points of the distances between the holes of each pair lying opposite an eyelet; and tensioning means comprising pairs of tension springs, the springs of each pair having their outer ends fixed in an eyelet and their inner ends respectively fixed in one hole of each associated pair of holes.
